CLAIM

The ornamental design for a respiratory device, as shown and described.

DESCRIPTION

FIG. 1 is an isometric view of a respiratory device with the mask in the closed condition showing my new design;

FIG. 2 is a side view of FIG. 1;

FIG. 3 is a front view of FIG. 1;

FIG. 4 is a back view of FIG. 1;

FIG. 5 is a top view of FIG. 1;

FIG. 6 is an isometric view of the respiratory device with the mask in the open condition showing my new design;

FIG. 7 is a side view of FIG. 6;

FIG. 8 is a front view of FIG. 6;

FIG. 9 is a back view of FIG. 6; and,

FIG. 10 is a top view of FIG. 6.
